HERMAN A. DAVENPORT, OF BROCKTON, MASSACHUSETTS, ASSIGNOR TO UNITED SHOE MACHINERY COMPANY, OF PATERSON, NEW JERSEY, A CORPORATION OF NEW JERSEY.

METHOD OF MAKING BOOTS AND SHOES.

1,169,068.

Specification of Letters Patent. Patented Jan. 18, 1916.

Application filed April 28, 1915. Serial No. 24,442.

To all whom it may concern:

Be it known that I, HERMAN A. DAVENPORT, a citizen of the United States, residing at Brockton, in the county of Plymouth and 5 State of Massachusetts, have invented certain new and useful Improvements in Methods of Making Boots and Shoes; and I do hereby declare the following to be a full, clear, and exact description of the invention, 10 such as will enable others skilled in the art to which it appertains to make and use the same.

The present invention relates to a method of making boots and shoes and more particularly to a method of making welt shoes.

In accordance with the usual method of making welt shoes it is customary to take a flat block sole which conforms in general outline to the desired shape, and to lay this 20 sole upon a partially completed shoe, securing it temporarily in place by cement or other adhesive substance. The sole laying operation serves the dual function of temporarily securing the outsole to the welted 25 shoe and shaping the outsole to approximately the desired form, both transversely and in a longitudinal direction. This shaping of the sole is accomplished by a yielding curved pressing pad which engages with the 30 outsole over substantially the entire area to impart the desired curvature to the sole. The transverse curvature imparted to the sole serves to bring the margins of the sole, especially at the shank, into close proximity 35 to the lasted upper. In that class of shoes having what is known as a close shank in which the margins of the sole, especially at the inner side of the shank, are located in close proximity to the upper, the projecting 40 margin of the block sole is brought into contact with the lasted upper if it is attempted in the sole laying operation to impart approximately the desired degree of transverse curvature to the sole. The projection of the 45 margin in this manner into close proximity with the lasted upper not only interferes with the subsequent operations which are performed upon the shoe, but sometimes necessitates the forcing of the marginal portion 50 of the sole away from the shoe and tends to counter-act, at least in part, the beneficial results of the sole laying operation. After the sole laying operation the edges of the outsole and welt are trimmed to approxi-

mately the desired shape by rounding mechanism which is controlled by a guide entering the crease formed by the junction of the welt and upper. If the marginal portion of the outsole has forced the welt into close proximity to the vamp portion of the upper the 60 crease guide is unable to enter fully into the crease and the trimming operation forms too great an extension edge. This in turn effects the location of the outseam, which follows the contour of the sole, and the line of 65 stitches at the shank instead of extending through the sole and welt in close proximity to the inseam, may be spaced at a considerable distance therefrom. Finally, in the sole leveling operation when it is desired to form a 70 close shank and bring the marginal portions of the sole into close proximity to the upper in order that the sole shall have a uniform transverse curvature throughout the entire width, the outer marginal portion of the sole 75 hinges at the outseam and if this seam is not located properly with relation to the inseam the sole cannot be shaped as desired.

According to the present improved method the foregoing and other disadvantages are 80 eliminated and the various operations may be performed upon the sole in the proper sequence and without interference to shape the outsole to the desired curvature and permit of its incorporation in the shoe.

To this end a feature of the invention consists in molding a flat sole to impart a predetermined transverse curvature to the central portion of a flat sole and a reverse curvature to the marginal portion of the 90 sole to cause the margin of the sole to stand out from the lasted upper when the sole is laid, while maintaining the predetermined curvature which has been imparted thereto. This method, as above outlined, permits the 95 desired transverse curvature to be imparted to the sole before its incorporation in a boot or shoe without affecting detrimentally the subsequent operations which are performed upon the shoe after the sole has been laid.

In the accompanying drawings illustrating the several steps in the present improved method of making a welt shoe; Figure 1 represents a cross section of a block sole with the two co-operating molding forms for 105 imparting the desired curvature to the sole; Fig. 2 represents a cross section of a lasted and welted shoe with the sole laid thereon,

taken upon the line 2—2 of Fig. 3; and Fig. 3 represents a side elevation of the shoe shown in Fig. 2.

In the manufacture of welt shoes the outsole before being incorporated in the boot or shoe is blocked out to approximately the desired shape and somewhat larger than the final size in order that it shall project beyond the welt around the entire margin of the shoe. According to the present method this block sole is positively molded between a pair of coöperating forms indicated at 1 and 2 respectively, which engage with the sole throughout the entire width to impart a predetermined transverse curvature to the central portion of the sole and a reverse curvature to the marginal portions of the sole to cause the edges of the sole to stand out from the lasted upper of the shoe when the sole is laid. Although in the preferred embodiment of the invention the molding forms engage with the sole throughout its entire width, it is obvious that if so desired the molds may be arranged to engage only with the central portion of the sole and a sufficient portion of the margin to impart a reverse break to the sole adjacent to the marginal portions, causing the edges of the sole to stand out. After the sole has been molded, as above described, it is laid upon the welted shoe in the manner shown in Figs. 2 and 3 with the marginal portion engaging with and extending beyond the welt 3 and the central portion conforming closely to the shoe bottom and surrounding the shank piece 4. The outsole shaped in this manner conforms closely to the shoe bottom and the marginal portions contact with the outstanding welt and may be secured thereto by adhesive material without depressing the welt into contact with the vamp portion of the upper, especially at the inner side of the shank. With the sole laid in this manner upon the welted shoe the subsequent operations upon the shoe including the rounding of the sole, the sewing of the outseam, and the leveling of the sole are facilitated as previously described.

Although the present invention contem-

plates a method of making boots and shoes 50 which consists in imparting a predetermined transverse curvature to the central portion of the sole, and a reverse curvature to the marginal portion of the sole, it should be understood that the term "reverse curvature" as employed contemplates any method which shall cause the marginal portion of the sole to extend in a direction opposite to the general direction of curvature of the central portion of the sole to form an outstanding margin, when the sole is laid upon the shoe. 55

While it is preferred to employ the specific construction and arrangements of parts shown and described, it will be understood that this construction and arrangement is not essential except so far as specified in the claims, and may be changed or modified without departing from the broader features 60 of the invention. 70

The invention having been described, what is claimed is;

1. The method of making boots and shoes which comprises molding a flat sole to impart a predetermined transverse curvature to the central portion of the sole and a reverse curvature to the marginal portion of the sole to cause the margin of the sole to stand out from the lasted upper when the sole is laid and laying the molded sole upon a lasted shoe while maintaining the predetermined curvature which has been imparted thereto. 75 80

2. The method of making boots and shoes which comprises molding a flat block sole 85 larger than the final desired size to impart a predetermined transverse curvature to the central portion of the sole, and a reverse curvature to the opposite marginal portions of the sole to cause the margins of the sole to stand out from the lasted upper when the sole is laid, and laying the molded sole upon a welted shoe with the outstanding margins 90 of the sole engaging with the welt while maintaining the predetermined curvature 95 which has been imparted to the sole.

HERMAN A. DAVENPORT.
